(57) **CLAIM**

The ornamental design for a trigger release locking handline hook, as shown and described.

DESCRIPTION

FIG. 1 is a side perspective view of a trigger release locking handline hook showing my new design.

FIG. 2 is a lower front perspective view thereof shown in an alternate position of use;

FIG. 3 is a rear elevational view thereof;

FIG. 4 is a left side elevational view thereof, the opposite side being a mirror image;

FIG. 5 is a front elevational view thereof;

FIG. 6 is a bottom plan view; and,

FIG. 7 is a top plan view thereof.
